HAIR SPRAY SHIELD

Lorraine S. McClain, Houston, Tex.

Application March 27, 1958, Serial No. 50,206

Term of patent 14 years

(Cl. D86—10)

Fig. 1 is a front elevational view of the hair spray shield showing my new design;

Fig. 2 is a side elevational view thereof; and

Fig. 3 is a perspective end view thereof.

I claim:

The ornamental design for a hair spray shield, as shown.
